UNITED STATES PATENT OFFICE.

JOHN A. ALBERTONI, OF AKRON, OHIO.

COAT-HANGER.

961,572.

Specification of Letters Patent. Patented June 14, 1910.

Application filed November 23, 1908. Serial No. 464,064.

To all whom it may concern:

Be it known that I, JOHN A. ALBERTONI, a citizen of the United States, residing at Akron, in the county of Summit and State 5 of Ohio, have invented a new and useful Improvement in a Coat-Hanger, of which the following is a specification.

This invention relates to a coat hanger and more particularly to folding coat hangers, 10 the object being to provide a coat hanger that can be folded so that it will occupy a very small space.

A further object of my invention is to provide a coat hanger which is so constructed 15 that when it is in a set up position it will be held rigid so as to hold the coat in the correct position.

A still further object of my invention is to provide a holding member in connection 20 with the cross tree which serves to hold the sections of the cross tree in the correct position and at the same time serves the purpose of holding a pair of trousers.

With these objects in view, my invention 25 consists in the novel features of construction, hereinafter described, pointed out in the claim and shown in the accompanying drawings, in which,

Figure 1 is a perspective view of my improved coat hanger showing it in position 30 to receive the coat. Fig. 2 is a side elevation showing the hanger folded. Fig. 3 is a detail view showing the manner of supporting the supporting hook and, Fig. 4 is a detail 35 section of the connecting rod.

In carrying out my improved invention I employ a sectional cross tree A which is formed of two sections pivotally connected together at B each section comprising a 40 substantially semi-circular portion A' having a large neck portion A². Tongues are punched out of the rear portion of one of the neck portions which are bent to form the guide eyes C in which is slidably mounted a hook D which is provided with a sliding 45 locking member E adapted to fit in notches A³ formed in the upper edges of the neck portions, these notches registering with each other when the cross tree is in a set up position so as to receive the locking member 50 which holds the cross tree firmly.

Pivotally connected to the ends of the shoulder portions A' of the cross tree A are

arms F between the outer ends of which are pivotally mounted the ends of tubular rods 55 G and G' which are pivotally connected together at G², the rod G' being provided with an overlapping end portion G³ so that when thrown into a horizontal position the rod will be held in this position so that a pair 60 of trousers can be thrown over the same.

It will also be seen that by this arrangement the cross tree will be held in position without the use of the locking member. The coat hanger is preferably formed of some 65 suitable sheet metal but it is of course understood that it can be formed of any material desired. By forming the same of thin metal a very light coat hanger can be formed so that it can be readily placed within a suit 70 case.

From the foregoing description it will be seen that I have provided a coat hanger, the cross tree of which is formed of two sections pivotally connected together and adapted to 75 be locked in a horizontal position by the locking member carried by the supporting hook.

What I claim is:—

As a new article of manufacture a coat 80 hanger comprising a sectional cross tree formed of two sections, each section comprising a substantially semi-circular portion having a large neck portion overlapped and pivotally connected together, the upper 85 edges of said neck portion being provided with notches adapted to register with each other when said sections are thrown into a horizontal position, guide arms formed on one of said sections, a hook slidably mounted within said guide arms, a slidably mounted locking member carried by said hook adapted to fit in said notches and hold said sections in a horizontal position, arms pivotally connected to the underside of said tree 90 sections adjacent their ends, tubular rods pivotally mounted between said arms, said rods being provided with ears pivotally connected together, one of said rods having an outwardly projecting portion overlapping 95 the end of the other rod for holding said rods in a horizontal position.

JOHN A. ALBERTONI.
